UNITED STATES PATENT OFFICE.

JOHN R. MEDLEY, OF ATLANTA, GEORGIA, ASSIGNOR TO HORACE E. CLARK, OF ATLANTA, GEORGIA.

HAT-BOX.

1,099,142.

Specification of Letters Patent.

Patented June 2, 1914.

Application filed November 28, 1913. Serial No. 803,553.

To all whom it may concern:

Be it known that I, JOHN R. MEDLEY, a citizen of the United States of America, residing at Atlanta, Fulton county, Georgia, 5 have invented certain new and useful Improvements in Hat-Boxes; and I do hereby declare the following to be a full, clear, and exact description of the invention, such as will enable others skilled in the art to which 10 it appertains to make and use the same, reference being had to the accompanying drawings, and to letters or figures of reference marked thereon, which form a part of this specification.

15 My invention relates to folding or collapsible boxes and particularly to hat boxes.

The object of the invention is to provide 20 a box of hexagonal form which, when unfolded will have the maximum amount of rigidity of boxes of this type and also to provide a box cover that can be contained within the box when both box and cover are folded.

In the accompanying drawings—Figure 1 25 is a perspective view, with parts broken away, of a box and cover embodying my invention. Fig. 2 is a transverse vertical section of Fig. 1. Fig. 3 is a vertical section of a partly collapsed box containing a 30 cover. Fig. 4 is a plan view of a folded cover, and Fig. 5 is a perspective view of a partly folded cover.

The sides of the box are preferably 35 formed of two pieces of card-board, 1 and 2, each piece being transversely creased at 1^a and 2^a respectively to form the faces 3 of the hexagonal body. Each piece 1 and 2 is provided with an end flap 4 formed by a transverse crease 5, and the lower end of 40 said flap is cut diagonally as shown at 6, Figs. 1 and 2, to facilitate folding. The lower end of each face 3 is formed with a flap 7, both ends of which are cut diagonally as shown at 8 to prevent said ends from 45 overlapping when the flaps are folded. The pieces 1 and 2 are connected by gluing the flap 4 of the piece 1 to the inner face of piece 2 and gluing the flap 4 of piece 2 to the inner face of piece 1.

50 The bottom of the box is formed of a single piece of card-board 9 cut in the form of a hexagon, the edges of which are the same length as the faces 3 of the box. The bottom is connected at two of its sides to 55 two parallel faces of the box sides by glu-

ing the underside of the flaps 7 to the top face of the bottom. The four other faces 3 are connected in pairs by triangular brace pieces 10, two edges of each brace piece being glued to the flaps 7 of two diverging 60 faces 3. The brace-pieces are under the bottom and act as supports for the free angular ends of the bottom 9.

To permit the box to be folded the bottom 9 is creased in the center on a line 11, which 65 runs parallel to the two edges, which are connected to the two faces of the sides and each brace piece is creased on a line 11' which runs from the apex of the angle to the center of the base of the angle. (Figs. 1 70 and 3.)

By making the bottom 9 in one piece and 75 of the same size as the box, accidental collapsing of the walls longitudinally of the crease line 11 is prevented.

The lid or cover 12 is made of a single 80 piece of card-board having flanges 13. These flanges are formed by making cuts into the edges of the cover at right angles to said edges, thereby forming notches of the proper angle that when the flanges are bent 85 at right angles to the cover, the adjacent ends of said flanges will be parallel as shown at 14, Fig. 1. These parallel edges are preferably connected by pieces of fabric. 85 To permit a ready folding of the flanges down onto the under face of the cover, diagonal creases 15 are formed in the flanges at one or both ends.

A tape 16 is provided by which the bottom 90 is held down onto the brace pieces 10, when the box is not collapsed. This tape rests on the inner face of the bottom 9 and passes out of the box through perforations 17 formed in the bottom at the base of the angular supports 10. The tape passes under 95 said supports into perforations 18 formed in opposite faces 3 near their lower edges and then out of the box through perforations 19 near the top of said faces and are tied together over the cover as shown in Fig. 1.

To fold the box, the top 12 is removed and the tape 16 is drawn upward from the bottom. The two parallel sides of the box, to which the bottom is attached, are then 105 pressed toward each other which pressure will cause the bottom 9 to fold inward (as shown in Fig. 3) on its crease line 11, and at the same time said pressure will cause the two pairs of converging sides to move 110

longitudinally of the crease line 11 in opposite directions and into the planes of said parallel sides. This movement of the converging sides will cause their triangular brace pieces 10 to fold inward on their crease lines 11' between the converging sides and into the planes of the bottom. When the box is completely folded the two parallel sides and the folded bottom are superposed while each of the two pairs of converging sides and the folded brace pieces are superposed.

In order that the cover 12 may be contained within the box when the latter is folded, said cover is creased on the line 15^a and when the cover is folded and placed in the box the cover rests on the folded bottom and has substantially the same dimensions as the bottom.

I am aware that hexagonal hat boxes have been patented in which the bottom is made up of a plurality of pieces, but no one of said pieces is of a sufficient size to extend into all of the angles formed by the sides as in the present instance. So far as I am aware, no lid for such a box has been patented which can be folded so as to be contained in the box.

I claim—

1. A collapsible hat box having six sides, a single piece bottom having six edges of the same length as said sides, two parallel edges of said bottom being connected to two parallel sides of the box, four of said edges being free, and all of the angles of said edges extending into the angles of the sides when the latter are spread apart.

2. A collapsible hat box having six sides, a single piece bottom having six edges of the same length as said sides, two parallel edges of said bottom being connected to two parallel sides of the box and all of the angles of said edges extending into the angles of the side when the latter are spread

apart, triangular pieces connecting the converging sides in pairs and arranged below the converging edges of the bottom, said bottom and triangular pieces being creased in their centers to permit folding of the same between the sides. 45

3. A collapsible hat box having six sides, a single piece bottom having six edges of the same length as said sides, two parallel edges of said bottom being connected to two parallel sides of the box and all of the angles 50 of said edges extending into the angles of the sides when the latter are spread apart, triangular pieces connecting the converging sides in pairs and arranged below the converging edges of the bottom, said bottom and 55 triangular pieces being creased in their centers to permit folding of the same between the sides, and a six sided lid having six flanges foldable onto the lid, and a crease in said lid extending to oppositely positioned 60 angles whereby said lid may be contained between the sides. 65

4. A polygonal collapsible box body collapsible on a diagonal thereof, a corresponding polygonal bottom having parallel sides secured to parallel walls of the body and folding on a like diagonal, folding bottom supports extending between adjacent sides across the ends of said bottom, said bottom and supports folding upwardly into the 70 body and a similar polygonal top having flanges, said top foldable on a diagonal and constructed to lie in the folded bottom when the box is collapsed. 75

In testimony that I claim the foregoing 80 as my invention, I have signed my name in presence of two subscribing witnesses.

JOHN R. X MEDLEY.
